MAGAZINE GRINDER

Charles Alexander Waterous, Brantford,
Ontario, Canada

Application June 29, 1933, Serial No. 678,296

10 Claims. (Cl. 83—75)

This invention relates to magazine grinder construction. In magazine grinders of the type where the logs are fed to a grinder pocket, under their own pressure, considerable difficulty is experienced in that the logs often tend to become jammed and packed in the magazine so that it is very difficult to operate the apparatus smoothly to load charges of logs into the grinding pocket.

An object of the present invention, therefore, 10 is to provide an arrangement for releasing the pressure between the logs as they approach the pocket of the grinder so that they may freely drop into the pocket and the smooth operation of the grinder in respect to feeding is positively assured.

A further object of the invention is to provide an arrangement permitting flexibility in at least one wall of the magazine which will be periodically available in the loading of the logs into the 20 pocket.

A still further object of the invention is to provide means of this character which may be operated automatically.

A still further object of the invention is to provide a means of this character which is of an extremely simple nature.

With these and other objects in view, the invention will be apparent from the following specification in conjunction with the accompanying 30 drawings which form part of the same.

In the drawings:—

Figure 1 is a sectional side elevation of a pocket grinder fitted with one practical form of means for providing flexibility in the wall construction 35 of the magazine.

Figure 2 is a top plan view of Figure 1, and,

Figure 3 illustrates another form of means for effecting a release of pressure between the logs as they approach the magazine.

Referring more particularly to the drawings, A 40 indicates the grindstone of any suitable grinder, B the magazine, C the grinding pocket and D the pressure shoe of the grinder.

As is usual, the logs are fed from the magazine B to the grinding pocket C and in the type 45 shown a shut off door 10 is provided between the magazine and the grinder pocket which is operated through a suitable cylinder 11, the piston rod 12 of its piston 13 being connected to the door so as to reciprocate it at the appropriate 50 moment to allow a charge to drop into the magazine and to prevent the next charge from entering. This control mechanism operates in conjunction with the control apparatus 14 of the 55 pressure shoe so that the operations synchronize.

Difficulty has been experienced, however, in the magazine in that the logs tend to pack and jam tightly so that when the closure door 12 is open to admit a charge to the pocket D the logs often fail to drop or will not drop immediately so that 5 the smooth operation of the structure is seriously interfered with. To overcome this difficulty, I arrange to provide for flexibility in the wall construction of the magazine B so that the pressure between the logs in the pocket is released as they 10 approach the pocket and the logs are permitted to drop without obstruction into the grinding pocket.

One form of practical construction is illustrated in Figure 1 consisting in a door or panel 15 adjacent to the grinding pocket which is hinged as at 16 so that it may, when released, swing outwardly thus relieving any pressure between the logs and the magazine walls. This flexibility in the wall construction is only designed to be 15 available periodically and in the form shown stop members 17 abut the panel or door 15 so that it is held rigid with the wall construction of the magazine. The stops 17 are carried in suitable 20 brackets 18 which are designed to operate with the shut off door 10, the brackets 18 being connected with the piston arrangement 13 so that when the door is opened the stops are retracted from contact with the door as illustrated in dotted lines in Figure 1. Thus, flexibility in the wall 25 construction of the magazine is immediately available and the pressure between the logs is released but upon closure of the door 10 the wall structure is again held rigid. The stop members 30 as shown may be in the form of adjustable screw 35 threaded members.

It will be realized that this is only one practical means for providing flexibility in the wall construction and that other means are equally applicable. For instance, it is possible to provide 40 a section of the grinder wall or walls in the form of a panel or section flexible in itself with means for holding the whole panel or section rigid, that is by backing it with a rigid construction which may be removed periodically to permit outward 45 expansion or flexing of the wall or walls. This form of construction and other forms working on a similar principle will effect the desired result.

Another form of construction for relieving pressure between the logs as they approach the 50 grinding pocket is illustrated in Figure 3. This consists in tapering a wall or opposite walls of the magazine as indicated at 19 so that as the logs are dropped to the lower regions of the magazine the pressure which ordinarily would 55

arise is relieved and the logs may be charged into the magazine without this hindrance.

The invention is particularly applicable to pocket grinders of the type including a shut off door and in that construction employing an arrangement for periodic flexibility in the walls it is preferable to provide for flexibility through an arrangement such as illustrated synchronizing with the operation of the door operating means. The log-holding device of the type used for controlling the charge to the pocket referred to in a co-pending application Serial No. 678,295 filed June 29th, 1933 may be used, this apparatus being illustrated in Figure 1 at E. However, where the grinder is of the single charge type or fitted with a holding device, in the constructions employing the principle of periodic flexibility, the side or sides of the magazine must be held to their inner rigid position while the single charge magazine is being loaded or when the logs are being dropped in the multiple charge magazine. It will be noted that when flexibility is permitted the structure, in effect, constitutes an arrangement having a tapered formation, the wall or walls sloping outwardly adjacent to the pocket which provides a construction similar to that as initially built into a magazine of the type illustrated in Figure 3.

Various modifications may be made in the invention without departing from the spirit thereof or the scope of the claims and, therefore, the exact forms shown are to be taken as illustrative only and not in a limiting sense, and I desire that only such limitations shall be placed thereon as are imposed by the prior art or are specifically set forth in the appended claims.

What I claim as my invention is:—

1. In a magazine grinder and in combination, a grinding pocket, a magazine positioned above the pocket, a shut off member operating between the pocket and magazine, a door mounted on one side of the magazine, said door being swingable outwardly from the magazine and an adjustable stop member movable with the shut off member designed to contact with the door when the shut off member is in its normal shut off position.

2. In a magazine grinder of the character described and in combination, a grinding pocket, a magazine from which wood is adapted to feed into the pocket, means between the pocket and magazine for controlling the passage of the wood from the magazine to the pocket and means on the side of the magazine cooperating with said control means for releasing the pressure of the wood in the magazine when the wood is being passed to said pocket.

3. In a magazine grinder and in combination, a grinding pocket, a grindstone, means in the pocket for feeding wood to the grindstone, a magazine extending upwardly from the pocket, means between the pocket and magazine for controlling the passage of wood from the magazine to the pocket, means at the side of the lower end of the magazine cooperating with said control means for releasing the pressure of the wood in the magazine when the wood is being passed to said pocket.

4. In a magazine grinder and in combination, a grinding pocket, a magazine separate from the pocket from which wood is adapted to feed into

the pocket, means between the pocket and magazine for controlling the passage of wood from the magazine to the pocket, an expansible section in the magazine adapted to permit the pressure of the wood therein to be released, said expansible section being operable during the passage of wood to said pocket, and means cooperative with the expansible section operable during certain periods of the operation for preventing expansion of said section.

5. In a magazine grinder in combination with a grinding pocket, a magazine from which wood is adapted to feed into the pocket, a hinged door on the magazine adapted to permit release of the pressure of wood therein during the passage of the wood to the pocket, means cooperative with the door operable during certain periods of the operation for preventing the opening of the door, and means between the pocket and magazine for controlling the passage of the wood from the magazine to the pocket.

6. In a magazine grinder of the character described and in combination, a grinding pocket, a magazine from which wood is adapted to feed into the pocket, means between the pocket and magazine for controlling the passage of wood from the magazine to the pocket, an expansible section in the magazine adapted to relieve the pressure of the wood therein during the passage of the wood to the pocket, and adjustable means cooperative with the said expansible section for preventing expansion of the said expansible section during certain periods of the operation.

7. In a magazine grinder of the character described and in combination, a grinding pocket, a magazine from which wood is adapted to feed into the pocket having an expansible wall section by which the pressure may be released, during the passage of the wood to the pocket, and means between the pocket and magazine for controlling the passage of the wood from the magazine to the pocket.

8. In a magazine grinder and in combination, a grinding pocket, a magazine from which wood is adapted to be fed into the pocket having a hinged door to one side thereof adapted to be moved outwardly to release the pressure in the magazine during the feeding of the wood to the pocket, and means between the pocket and magazine for controlling the passage of the wood from the magazine to the pocket.

9. In a magazine grinder and in combination, a grinding pocket, a magazine from which wood is adapted to be fed into the pocket having an expansible wall, and means associated with the wall for periodically controlling the expansion of the same.

10. In a magazine grinder and in combination, a grinding pocket, a magazine from which wood is adapted to be fed into the pocket having an expansible wall, means associated with the wall for periodically controlling the expansion of the same, means between the pocket and magazine for controlling the passage of wood from the magazine to the pocket and means for synchronizing the expansion of the magazine wall with the operation of said last mentioned controlling means.
